LINE CLAMP

Stephen P. Becker, Poughkeepsie, N. Y., assignor to Fargo Mfg. Company, Inc., Poughkeepsie, N. Y., a corporation of New York

Application April 26, 1955, Serial No. 503,889

2 Claims. (Cl. 339—264)

This invention relates to a structurally and functionally improved clamp for mechanically and electrically connecting electrical lines to each other, which lines may carry high voltage.

The present application is a continuation-in-part of my earlier application for patent entitled "High-Voltage Clamp," Serial No. 170,653, filed June 27, 1950, now abandoned.

Among the objects of the present invention are those of providing a clamp for electrical transmission lines, which clamp may readily be manipulated to electrically and mechanically secure lines to each other, or to disconnect those lines and which, in use, will maintain the connection for long periods of time with freedom from all difficulties, the clamp being simple in design and operation.

With these and other objects in mind, reference is had to the attached sheet of drawing, illustrating practical embodiments of the invention, and in which:

Fig. 1 is a sectional side view of the clamp;

Fig. 2 is a front elevation thereof;

Figs. 3, 4 and 5 are sectional views taken along the lines 3—3, 4—4 and 5—5 in the direction of the arrows as indicated in Fig. 1;

Fig. 6 is a side elevation of the clamp; and

Fig. 7 illustrates an alternative form of structure.

In these views the numeral 10 indicates a metallic sleeve, the bore of which is interrupted by a preferably integral abutment in the form of a flange 11. Beyond the latter a guide structure is furnished by preferably providing an axially-extending groove 12 in the bore, which groove may terminate in an end wall 13. It is also preferred to have wing portions 14 extending outwardly from the lower end of sleeve or tube 10.

A screw-threaded socket member 15 has a diameter such that it may be accommodated within the bore of the sleeve at a point above flange 11. Adjacent its lower end this member may have an out-struck portion 16 which rides within groove 12 to furnish—in cooperation with the same—a key and keyway structure preventing a rotation of the socket member with respect to the sleeve. After these parts are operatively associated, the closing wall or stop 13 is conveniently provided. This may be accomplished by resorting to any acceptable technique to extend portion 13 in the direction of the axis of the assembly and thus overlie part 16.

Socket member 15 carries, as a preferably integral part, a wire-engaging and clamping jaw. That jaw, as shown, embraces an outwardly-extending portion 17 continued in the form of angularly-extending faces 18, the last two of which converge to define a V-notch or trough suitable for the reception and retention of a cable or lead 19. The jaw provided by portion 17 and its continuations may be rigidified by a transversely-extending rib or fin portion 20, also integral with member 15 and terminating substantially in line with the upper end of the latter. This fin may be formed with an opening 21.

As shown, the sleeve 10 has its forward face interrupted to permit portions 17 and 18 to extend outwardly of the

2

unit. At the base of this interruption, a jaw or supporting part 22 extends outwardly from the sleeve or tube. The face 23 of this jaw again preferably includes surfaces extending angularly with respect to each other to generally provide a centering trough or V-shaped configuration opposed to that furnished by the surfaces 18. Inwardly of the faces 23 jaw 22 may include an inwardly and downwardly-extending surface 24.

The threads of socket member 15 are engaged by the threads of a bolt 25. The latter may be provided with a head portion 26 in the form of a ring suitable for engagement with the operative end of an applying or mounting tool (not shown). This bolt is furnished with a collar or flange 27, having a diameter less than that of the bore of sleeve 10. The underface of this flange is conveniently beveled and engaged by a retaining ring 28 seating within a groove formed in the adjacent end of sleeve 10 to prevent a displacement of the bolt. A spring 29 is interposed between flange or collar 27 and flange 11. In the position of the parts as shown in Fig. 1, this spring is substantially fully expanded so as not to exert unnecessary tension.

To furnish a clamp for a lead or tap-off line, a wing portion 30 may extend outwardly from the side face of sleeve 10 and be integral therewith. As shown especially in Figs. 3, 4 and 5, this wing portion will include side walls 31, spaced from each other, and which side walls may be notched in their upper edges as indicated at 32. A bolt has its shank 33 extending through an opening provided in the wing portion between walls 31. This bolt is secured in position by, for example, a nut and washer assembly 34. The inner end of the bolt terminates in a preferably ring-shaped body 35, which includes at its end a head portion 36. The length of the latter is greater than the width of ring 35. Therefore, its ends overlap walls 31 and the notched edges 32 thereof.

In conclusion, it will be observed that the inner end of bolt 25, preferably terminates substantially in the upper plane of tube or sleeve 10. Also, the side walls of the latter above the supporting or jaw portion 22 may generally define an ellipse. Similarly, the adjacent surfaces of socket member 15 may include an identical configuration. It will be understood, if such a structure is resorted to, any danger of the socket member oscillating or turning with respect to the sleeve will be prevented. This, of course, will also be prevented by the key and keyway structure and could be satisfactorily counteracted by having the surfaces of the sleeve member and socket of any desirable non-circular outline.

In use, it will be assumed that a lead (not shown) is introduced through the loop or ring 35 of the bolt. That lead will rest within notch surfaces 32 and as the nut assembly 34 is tightened, head portion 36 will engage the outer peripheral surface of the lead to draw the latter into firm contact with the outer edges of walls 31. This action will be continued until the parts are clamped against movement. Under those circumstances, the lead will be in proper electrical connection with the tube 10. The clamp is now ready for application to a current-supplying or receiving lead, such as 19. That line may customarily be supported in a generally horizontal plane.

Bolt 25 will be actuated to assure a substantial separation of jaw surfaces 18 from surfaces 23. This will provide clearance such that an operator who may be gripping bolthead 26 by means of a "hot stick" will be able to move the guiding portion 17 of the jaw assembly over and into engagement with the lead 19. Thereupon, the latter will shift to rest between converging surfaces 18, as shown in Fig. 1. If, now, by engaging the lead, or by the use of a suitable instrument, sleeve 10 is prevented from rotating and bolt 25 is rotated, the jaw structure 17—18 will be drawn towards the jaw structure 22. This action will serve to clamp between these elements the lead

19. Therefore, again a properly firm mechanical and electrical connection will be established, such that current may flow to or from lead 19 and from or to a lead associated with loop 35.

It will be understood, even if line 19 is not properly disposed with respect to the jaw surfaces, an acceptable engaging and clamping structure will nevertheless be furnished. This has been illustrated in Fig. 6, in which line or cable 19 has been shown as displaced into engagement with surface 24. It is apparent that so positioned, the cable will nevertheless be firmly gripped. Also, by this structure a design is furnished which will prevent any jamming of the parts, even if the cable or an auxiliary strand is shifted to too great an extent inwardly toward the axis of the device. In any event, it will be appreciated that as the jaws are tightened to firmly engage the cable or line 19, collar or flange 27 of the bolt 25 will move inwardly as the resistance to movement on the part of jaws 17-18 increases beyond a certain extent. Therefore, the grip on the cable or line exerted by the jaws will actually be equal to the degree of compression of the spring, dependent upon the amount bolt 25 has been tightened. This construction will also provide a yieldable engagement which will vary according to the tension or strain which is exerted upon the parts.

In the form of structure shown in Fig. 7, the same arrangement of parts as that heretofore described has been illustrated. However, in this construction, the tube member 10 providing the faces 23 of the lower jaw is furnished with wing portions 40. These will serve as guides in engagement with the wire in order to position the latter properly between the jaws. It is apparent that by this construction the wire cannot be displaced to a position where it will be locked to the rear of the groove or engaging surfaces.

Thus, among others, the several objects of the invention as specifically aforementioned are achieved. Obviously, numerous changes in construction and rearrangement of the parts may be resorted to without departing from the spirit of the invention as defined by the claims.

I claim:

1. A line clamp including in combination a sleeve, an abutment extending into the bore of said sleeve, a socket member slidably mounted by extending into the sleeve bore, a key and keyway forming parts of said sleeve and member to prevent relative rotation thereof, a bolt extending from a point beyond said sleeve into the bore of said member, such bore and bolt being formed with cooperating screw-threads, a flange extending outwardly from said bolt and within the bore of said sleeve, a spring interposed between said abutment and flange, means mounted by said sleeve and engaging said flange to prevent an outward displacement of said bolt by said spring and jaws extending outwardly from said sleeve and member and cooperating to grip between them a cable.

2. In a line clamp as specified in claim 1, said key and keyway embracing an outstruck portion adjacent one end of said member, said sleeve being formed with a groove between said abutment and the end adjacent which said member is disposed, said groove extending axially of said sleeve and slidably receiving said abutment and an end wall forming a part of said sleeve and closing said groove to prevent said outstruck portion from riding out of the same.
